UNITED STATES PATENT OFFICE.

JOHN A. JOHNSTON, OF SPRINGFIELD, MASSACHUSETTS.

SPREADER FOR ROAD MATERIAL.

Application filed March 1, 1921. Serial No. 448,753.

To all whom it may concern:

Be it known that I, JOHN A. JOHNSTON, a citizen of the United States, residing at Springfield, in the county of Hampden and 5 State of Massachusetts, have invented a new and useful Spreader for Road Material, of which the following is a specification.

This invention relates to a device particularly designed for spreading stone or other 10 similar material over a prepared surface. In road construction it is customary to prepare a foundation and place thereon an upper layer of crushed stone, gravel, or other suitable material which should present 15 a smooth and uniform surface.

It is the general object of my invention to improve the construction of spreaders for such purposes and to provide a spreader by which a layer of road material of any 20 desired thickness may be deposited at a minimum expense of time and labor.

With this general object in view, an important feature of my invention relates to the provision of novel supporting devices 25 for a spreader, capable of adjustment to adapt the machine to different working conditions.

Another feature of my invention relates to improved devices for attaching and 30 partially supporting my improved spreader on a truck or wagon.

My invention further relates to arrangements and combinations of parts which will be hereinafter described and more particularly pointed out in the appended claims.

A preferred form of my invention is shown in the drawings in which

Fig. 1 is an end view of my improved spreader;

Fig. 2 is a partial plan view thereof;

Fig. 3 is a partial rear elevation;

Fig. 4 is a rear elevation of a modification; and

Fig. 5 is a detail section on the line 5—5 of Fig. 4.

Referring to the drawings, my improved spreader comprises an open body having an inclined front side 10, a substantially vertical rear side 11, and ends 12. The bottom of the body is open at 13 to provide an exit for the material to be spread. The body is supported upon a pair of shoes or runners 14 disposed on each side thereof.

Each runner 14 is preferably pivoted at 15 to the rear end of a forked arm 16 which in turn is pivoted to the body at 17. An ad-

justing screw 18 for each runner is threaded in a bracket 19 secured to the body of the spreader, and engages a U-shaped upward projection 20 of the arm 16.

By adjusting the screws 18 the runners may be held at any desired distance below the bottom of the spreader body, thus regulating the thickness of the layer of material to be deposited.

The front ends of the runners 14 may be connected by a tie-rod 21 pivotally secured to each runner to permit changes in the relative elevation thereof.

A pair of bars 22 extend forward from the body of the spreader and are rigidly secured to the front side 10, as clearly shown in Fig. 1, a brace 23 being provided for the upper portion of the body. The bars 22 are adapted to rest upon the rear axle 75 or other part or attachment of the truck or wagon by which the spreader is drawn, and thus support a material part of the weight of the spreader and its load.

I also provide a chain 24 for each bar 22, 80 said chain having a hook 25 at one end adapted to engage the axle or other supporting part of the truck, and having its opposite end secured to a crank shaft 26. By means of this crank shaft, the spreader may 85 be drawn forward to the desired operative relation with the truck body, where it is held in position by a pawl 27 engaging a ratchet wheel 28 on the crank shaft 26. Folding braces 29 support the body when 90 detached from the truck.

I find it frequently desirable to provide an adjustable outlet plate at the rear of the spreader, as shown in Figs. 4 and 5. This plate may consist of an angle iron 95 30 secured by bolts 31 to the rear side 11 of the spreader and is engaged at each end by an adjusting screw 32 threaded in a bracket 33 on the side 11. By suitably adjusting the plate 30 the contour of the 100 finished surface may be made straight or it may be crowned to meet the actual conditions of use.

From the foregoing description it will be seen that my improved spreader is of 105 simple and durable construction, and that it is adapted to deposit a uniform layer of road material of any desired thickness, which thickness may be changed at any time by adjusting the runners 14 by means 110 of the screws 18.

Separate adjustment of each runner per-

mits the spreader to operate under most unfavorable conditions, as when one side of the spreader must be supported upon finished road material while the other rests upon the rough surface of the underlying foundation.

The runners may also be separately adjusted so that the material will be spread uniformly or with a greater thickness at one side than at the other. It is also possible to lower the spreader so that it rests directly upon the road surface and deposits stone in any depressions thereof. The long base provided by the runners bridges over local inequalities in the prepared road bed and thus prevents the reproduction of these inequalities in the finished surface, a common result where the spreader is supported upon wheels which readily drop into such local depressions. The adjustable outlet plate at the rear of the spreader permits me to spread road material with any desired crown or curvature of the resulting surface.

It will be also evident that changes and modifications can be made in my invention within the spirit and scope thereof, as set forth in the claims, and I do not wish to be otherwise limited to the details herein disclosed, but what I claim is:—

1. A spreader for road material comprising an open body having side and end walls and having an opening in the bottom thereof, and adjustable means to support said body at any desired elevation above the surface on which the material is to be spread.

2. A spreader for road material comprising an open body having side and end walls and having an opening in the bottom thereof, and a separately adjustable support for said body at each end thereof, by which said body may be held at a selected elevation.

3. A spreader for road material comprising an open body having side and end walls and having an opening in the bottom thereof, and a pair of runners adjustable to support said body at any desired elevation.

4. A spreader for road material comprising an open body having side and end walls and having an opening in the bottom thereof, a pair of runners for said body, and means to separately adjust said runners relative to said body, whereby the elevation of the body may be varied.

5. A spreader for road material comprising an open body having side and end walls and having an opening in the bottom thereof, a pair of runners for said body, arms pivotally connecting said runners to said body, and adjusting screws mounted on said

body and engaging said arms to support said body above said runners.

6. A spreader for road material comprising an open body having side and end walls and having an opening in the bottom thereof, and means to attach said spreader to a truck and to support a portion of the weight of said spreader on said truck.

7. A spreader for road material comprising an open body having side and end walls and having an opening in the bottom thereof, bars fixed to said body and adapted to engage and be supported by a portion of the truck, a hook and chain mounted on each bar for attachment to said truck, and a take-up mechanism for said chains.

8. A spreader for road material comprising an open body having side and end walls, and having an opening in the bottom thereof, an outlet plate mounted on the rear wall, and means to vary the curvature of said outlet plate.

9. A spreader for road material comprising a body having end and rear walls, an inclined front wall, and an opening in the bottom, means to support a portion of the weight of said spreader on the road bed and means to attach said spreader to a truck and to support the remainder of the weight of the spreader thereon.

10. In a road metal distributer including a hopper-shaped body entirely open at its bottom, road engaging supporting members operatively engaged with the body, the body and the road engaging supporting members being mounted for relative adjustment vertically.

11. A road metal distributer including a hopper-shaped body having downwardly converging front and rear walls and vertical end walls, the lower edges of the front and rear walls being spaced from each other to provide a discharge opening, road engaging members disposed below the ends of the body and having upwardly extending shanks, and means operatively engaging the shanks and the body whereby the body may be raised or lowered relative to the members.

12. A spreader for road material comprising an open body having side and end walls and having an opening in the bottom thereof, a support for each end portion of said body by which said body may be held at a desired elevation above the surface on which the material is to be spread, and means to adjust the said supports to change the elevation of said body.

In testimony whereof I have hereunto affixed my signature.

JOHN A. JOHNSTON.
